[57] **CLAIM**

I claim the ornamental design of a panel for an exit sign having a curved face, as shown and described.

DESCRIPTION

FIG. 1 is a perspective view of the invention, shown in relation to an exemplary sign housing, and having exemplary indicia and marking thereon;

FIG. 2 is a front view of the invention, shown having exemplary indicia thereon;
FIG. 3 is a top view of the invention;
FIG. 4 is a bottom view of the invention;
FIG. 5 is a right side view of the invention; and,

FIG. 6 is a left side view of the invention.
The broken lines are shown for illustrative purposes only,
and form no part of the claimed design.
